UNITED STATES PATENT OFFICE.

WILLIAM NEILL HOWELL, OF PHILADELPHIA, PENNSYLVANIA, ASSIGNOR TO SIMON LAKE, OF BRIDGEPORT, CONNECTICUT.

PERISCOPE.

959,013.

Specification of Letters Patent. Patented May 24, 1910.

Application filed July 6, 1907. Serial No. 382,528.

To all whom it may concern:

Be it known that I, WILLIAM NEILL Howell, a citizen of the United States, and a resident of Philadelphia, in the county of Philadelphia and State of Pennsylvania, temporarily residing in London, England, have invented a certain new and useful Improvement in Periscopes, of which the following is a full, clear, and exact description.

This invention relates to periscopes for use in submersible vessels of all kinds, and especially submarine torpedo boats.

Briefly stated, the object of the invention is to provide an instrument by which a view of the entire horizon may be had by the occupant of the vessel at all times, when the vessel is running beneath the surface of the water with only the upper end of the instrument projecting above the surface, and without requiring an adjustment of the instrument, as has hitherto been necessary, in order to obtain a view in any given direction other than the one to which the instrument is set at the time.

With the instruments now in use, it is necessary for the steersman, or observer, to keep his eye directed upon the instrument, the same as in looking through an ordinary field-glass, and to manually turn the instrument when it is desired to view the horizon in different directions. This operation is exceedingly disadvantageous, since it not only requires the observer to concentrate his eye directly on the instrument, but also necessitates the manual operation of the instrument to shift it, and this last is accomplished with difficulty, owing to the tight-fitting bearings and stuffing-boxes in which the instrument is mounted.

In order to overcome these objectionable features, I provide a rapidly revolving observing tube, having the usual prisms or reflectors which are adapted to reflect to the observer all objects at any point on the horizon, whereby the operator is enabled to observe an object lying in any direction with reference to his vessel or approach to his vessel from any direction. This assists in a precision of aim of the vessel at an hostile vessel, but also enables the occupants besides the steersman to observe the interior of the vessel.

the vessel may station themselves to observe in other directions, and thus it is possible to ascertain the approach of a vessel or vessels from various directions.

With my arrangement, an image is reflected into the vessel the same as in other instruments, it being only necessary for the observer to change his position in order to obtain a view in any given direction.

The invention also comprises certain peculiar structural features and arrangements of the operative parts of the device, all as will be described fully and then particularly claimed.

In the accompanying drawings, illustrating the invention, in the several figures of which like parts are similarly designated. Figure 1 is a sectional elevation of the upper portion of a vessel showing the improvement in position. Fig. 2 is a vertical longitudinal section of the same, on a larger scale. Fig. 3 is a diagrammatic view.

A designates a portion of the deck or conning tower or turret of a submarine vessel, in which is securely mounted a tubular casing or support B, which projects through the vessel to any desired height, and is preferably provided with a gland-ring C, to prevent ingress of water through the opening of the vessel through which the casing B extends. Near the upper and lower ends of the casing are arranged bearing-rings D, in which is mounted an observing tube E, having collars or flanges E', co-acting with the bearing-rings D by means of interposed antifriction balls, which permit a free rotary movement of the tube.

F and F' are optical prisms or reflectors secured in any suitable manner at opposite ends of the tube E, respectively, each prism having its reflecting face inclined at such an angle with the axis of the observing tube that an image of an external object received through the prism F, will be reflected downwardly through the tube into the interior of the vessel through the prism F', for the inspection of the observer. In practice I may use a system of lenses, to give a wider field of vision than could be had by the prism alone, or a lens or system of such lenses.

secured to the lower end of the tube E by a belt H', etc.

ending from a pulley I' of a suitable electric motor I to which current may be supplied through the dynamo or storage batteries (not shown) of the vessel.

The upper end of the tubular casing B is closed by a cylindrical glass hood K, which may be held in place by cement and a collar K', and has its upper end closed by a metallic cap K², or an integral glass cap. The glass is sufficiently heavy to withstand external pressure and protect the prism F and lens G from the water when the vessel is running with only the upper end of the sighting instrument exposed.

In order to insure against ingress of water into the vessel, should the hood become injured, the lower end of the casing B is provided with a screw-cap L, having a packing-ring L', which is designed to engage the lower face of the pulley H, when the screw-cap L is turned up tight upon the casing, thereby sealing the lower end of the tube and preventing any possible ingress of water to the vessel. Of course, when the screw-cap is to be applied to the casing as described, the belt H' is removed from the pulley.

While I have shown a belt and pulleys for operating the observing tube, it is to be understood that the tube may be operated by gears or any other suitable mechanism, and I, therefore, do not wish to limit myself to the exact features shown.

In the use of the instrument so far described, the motor is geared to revolve the tube at a very high rate of speed, say, for example, 1000 R. P. M., so that a reflected ray of light from any object within the field of vision will strike the eye of the observer once in every revolution of the tube, and owing to the great number of reflections impressed upon the eye, the effect will be the same as though the tube and prisms were held stationary and bore continuously upon the object. It will be seen, therefore, that the observer can quickly obtain a view in any direction without the necessity of shifting, turning, or adjusting the instrument in any manner.

With the instruments commonly in use, and assuming that they should be set to point directly ahead, and it is desired to obtain a view to port or starboard, say for a radius of 45°, the instrument must be shifted and the eye of the observer centered upon the eye-pieces. This shifting is not readily accomplished, since the instruments are difficult to turn, owing to their bearings in stuffing boxes, but, with my instrument, it is only necessary for the observer to shift his position so as to look in the direction at any point in order to obtain the desired view.

Referring to Fig. 3, X indicates the lower end of the

a, the direction in which the prism is revolved. Should it be desired to look directly ahead, the observer looks at the instrument in the direction indicated by the arrow 1. By changing his position to either side of the prism, and looking in the direction indicated by either of the arrows 2, he can obtain a view in either direction upon the horizon. Likewise, a view can be had of the entire horizon by simply walking around the instrument.

It will be understood that field glasses may be employed to look into the prism F, to magnify the object; and a separate range finder may also be used in connection with the periscope for getting the range of distant objects.

From the foregoing, the advantages of my improvement will be readily apparent to those skilled in the art to which my invention appertains, and further statements as to its usefulness are thought to be unnecessary.

What I claim is:—

1. The combination with a submergeable vessel, of a rotatable observing tube projecting from the vessel and containing reflecting means, and means for rapidly rotating said tube.
2. The combination with a submergeable vessel, of a rotatable observing tube projecting from the vessel, prisms located at the upper and lower ends of the tube, and means for rapidly rotating the tube continuously while in use.
3. The combination with a submergeable vessel, of a rotatable observing tube projecting from the vessel, prisms located at the upper and lower ends of the tube, a lens located adjacent to the prism at the upper end of the tube, and means for rapidly rotating the tube.
4. The combination with a submergeable vessel, of a rotatable tube projecting from the vessel, prisms arranged at the upper and lower ends of the tube, and means operatively connected to the tube for rapidly rotating it.
5. The combination with a submergeable vessel, of a support, a rotatable observing tube journaled in the support and containing reflecting means, and means for rapidly rotating the tube continuously while in use.
6. The combination with a submergeable vessel, of a support, a rotatable observing tube journaled in the support and having prisms at its upper and lower ends, a tubular hood arranged over the upper end of the tube, and means for rapidly rotating the tube.
7. The combination with a submergeable vessel, of a support, a rotatable observing tube journaled in the support and having a tubular hood arranged over the upper end of the tube, and means for rapidly rotating the tube.

inner end of the support, for the purpose specified.

8. The combination with a submersible vessel, of a support projecting outwardly therefrom, an observing tube journaled in the support, a prism carried at each end of the tube, a transparent hood arranged at the outer end of the support, means for rapidly rotating the tube and adapted to be disconnected therefrom, and means for temporarily closing water-tight the lower end of the support when the rotating means is disconnected.

9. The combination with a submersible vessel, of a tubular support projecting outwardly therefrom, a transparent hood arranged over the outer end of the support, an observing tube journaled to the support and having prisms arranged at opposite ends thereof, a pulley carried by the tube adjacent to its lower end, a motor having its drive shaft provided with a pulley, and a belt connecting the pulleys.

10. A periscope, comprising a support, an observing tube journaled therein and provided with prisms at opposite ends thereof,

means for rapidly rotating the tube and adapted to be disconnected therefrom, a transparent hood arranged over the upper end of the support, and means for closing the lower end of the support when the operating means is disconnected.

11. A periscope, comprising a support, an observing tube journaled therein and provided with reflecting means, a pulley secured to the tube adjacent to its inner end, means for operating upon the pulley for rapidly rotating the tube and adapted to be disconnected therefrom, a hood held upon the end of the support, and a screw-cap adapted to be fitted upon the opposite end of the support when the operating means is disconnected, and packing interposed between the screw-cap and pulley for closing the said support water-tight.

In testimony whereof I have hereunto set my hand this 25 day of June A. D. 1907.
